STACKING MACHINE

Hugh W. Gabbert, Norwood, Ohio, assignor to
 The American Laundry Machinery Company,
 Norwood, Ohio, a corporation of Ohio

Original application June 24, 1940, Serial No.
 342,045. Divided and this application August
 14, 1940, Serial No. 352,545

9 Claims. (Cl. 271—87)

This invention relates to improvements in machines for stacking and counting fabric articles.

This application is a division of my copending application Serial No. 342,045, filed June 24, 1940, to which reference may be had for a more complete description of the complete machine.

Among the objects of the present invention are the provision for stacking articles in a vertical stack by means of a conveyor which moves the articles to the stack and also raises the articles into position in the stack; the provision of a conveyor for moving articles to a stacking plate and positioned at an angle adjustable with respect to the stacking plate so that flimsy articles may be handled without mussing; the provision of means for vertically stacking articles and means for holding the articles elevated in the pile, together with means for simultaneously raising the stacking means and lowering the holding means so as to more efficiently accomplish the stacking operation, and the provision of novel parts of the stacking mechanism and the stack holding means as will be later described.

Other objects and advantages of the present invention will be apparent from the accompanying drawings and specification and the essential features thereof will be set forth in the claims.

In the drawings, Fig. 1 is a side elevation of a combined folding and stacking machine embodying my invention; Fig. 2 is an enlarged fragmental detail view of the clutch mechanism taken substantially in the position of the line 2—2 of Fig. 5; Fig. 3 is a partial sectional view taken on the line 3—3 of Fig. 2; Fig. 4 is a central longitudinal section taken toward the right end of Fig. 1; Fig. 5 is an enlarged fragmental view of the clutch mechanism looking in the direction of the arrows 5—5 of Fig. 1; Fig. 6 is an enlarged rear end elevation of the machine showing the stacking device; Fig. 7 is a detail view looking in the direction of the arrows 7—7 of Fig. 6; while Fig. 8 is an enlarged detail sectional view of the conveyor belt adjusting mechanism taken along the line 8—8 of Fig. 4.

In the embodiment of my invention here illustrated, the entire folding and stacking mechanism is supported on the general framework 20. This framework supports a table along which the article is moved for the longitudinal folding operation and which comprises in general a plate 21 which extends from the front of the machine to the point 22 (Fig. 4) toward the rear of the machine near the cross folding apparatus. As best seen in Fig. 1, this table extends first upwardly at a rather steep angle to provide the 55

necessary elevation and thereafter downwardly past the wings which produce the longitudinal folds in the article. A conveyor belt 24 serves to carry the article through the longitudinal folding portion of the machine. This conveyor belt passes around a drive roller 25 at the front of the machine, thence over the surface of the table 21, over the roller 26 at the rear of the machine and returns over the idler rollers 27 and 28 near the front of the machine.

The means for cross folding the article comprises the folding rollers 46 and 47 which are journaled in brackets 48 and 49 carried on the machine frame. The shaft 46a of roller 46 rides in slots in the supporting brackets and springs 50 yielding urge roller 46 toward roller 47 so as to permit the passage of the article between the rollers. The drive for the folding rollers is shown in the above mentioned copending application. Referring to Fig. 4, the shaft of roller 26 (which is driven by conveyor belt 24) carries a sprocket which is connected by a chain with a sprocket which is secured to one end of the shaft of roller 47. On the other end of this shaft is the pinion 47b which meshes with pinion 46b carried by the shaft for roller 46 so that the folding rollers turn in unison and in opposite directions.

The means for feeding the longitudinally folded article to the cross folding rollers comprises a folding blade 54 mounted on arm 55 which is pivotally mounted on a portion of bracket 35. Means for actuating the folding blade is connected at the forward end of rod 57 which passes through an opening in the arm 55b and motion is transmitted from rod 57 to arm 55b through a coil spring 58 which is secured between the arm and the collar 59 on the end of the rod. As best seen in Fig. 2 the rod 57 extends to the front of the machine where it is pivotally connected to the free end of an arm 60 which in turn is pivotally mounted at 61 on a bracket 62 connected with the machine frame. On an intermediate portion of the arm is mounted a roller 63 which coacts with a cam 64 which in turn is rigidly secured to a sleeve 65 (Fig. 3) which is freely rotatable on the shaft 66 which in turn is journaled in the machine frame. The drive means for cam 64 and sleeve 65 is a one-revolution clutch mechanism best shown in Fig. 2 which will presently be described. The actuation of this one-revolution clutch mechanism is controlled by the armature of solenoid 67, the energization of which is accomplished by finger 68 arranged in the path of the article as it moves along the aux-

iliary table portion 44 toward the rear of the machine.

The closing of the mercury switch 69 completes the energization of the solenoid 67 which is in circuit with the electrical supply lines for the machine driving motor 73 so as to initiate actuation of the clutch mechanism of Fig. 2. The drive for the folding apparatus is as follows: Motor 73 which is carried by the frame of the machine is connected by driving belt 74 with a pulley 75 on shaft 76 which is suitably journaled in the frame. A sprocket 77 on shaft 76 is connected by chain 78 with a sprocket 25a on the shaft of the conveyor drive roller 25. A pulley 79 on shaft 76 is connected by belt 80 with a pulley 81 on shaft 66. Keyed or pinned on shaft 66 is the toothed wheel 82 which therefore rotates continuously. The one-revolution clutch mechanism of Fig. 2 comprises an arm 83 rigidly secured to sleeve 65 and in the present instance integral with the cam 64. A latch member 84 is pivotally connected to the free end of this arm. This latch member comprises portions 84a and 84b. 84a has a bifurcated end which supports a pin 85 adapted to engage between the teeth of wheel 82 and biased toward engagement by the spring 86. The pin 85 is normally held out of engagement with the wheel teeth by means of a stop 87a on arm 87 which engages the portion 84b of the latch member. The arm 87 is pivotally mounted at 88 on a bracket 89 which also supports the solenoid 67. The armature 67a of the solenoid is pivotally connected to the free end of arm 87. When the leading end of the longitudinal folded article actuates switch 69 and energizes solenoid 67 the armature 67a is lifted so as to disengage the stop 87a from the latch member 84 which permits the pin 85 to engage between the teeth of wheel 82. The continuously rotating wheel then carries arm 83 and cam 64 through one revolution so as to actuate the folding blade 54 through arm 60, rod 57 and arm 55b. This causes downward movement of blade 54, feeding the longitudinally folded article between the cross folding rolls. As soon as the article is moved out of engagement with the arm 68 the switch 69 is so constructed that it returns to its circuit-opening position thus deenergizing solenoid 67. The armature 67a therefore drops bringing stop 87a into the path of the latch member portion 84b so that when it has made one revolution the latch member strikes the stop and lifts the pin 85 out of engagement with the wheel 82.

The stacker mechanism comprises a combined chute and stacker plate 105 best seen in Fig. 4 which is carried by a frame structure which is mounted to freely oscillate about the shaft 106 supported by the machine frame. The plate 105 at its forward and upper end is substantially the full width of the folding machine channel so as to receive a folded article. At the point 107 (Figs. 4 and 8) the plate narrows and from there to the rear end of the plate the portion 105a extends between a pair of conveyor belts 108. These belts at their forward ends pass around pulleys 109 which rotate with shaft 106 and at their rearward ends pass around rollers 110 which are adjustably supported in the stacker frame. The conveyor belts intersect the plane of the plate 105 at an angle, the conveyor belts lying above the plane of the plate at the point 107 and lying below the plane of the plate at the rear end of the stacker. The purpose of this arrangement is to provide a pos-

itive movement of the article as it enters the stacking apparatus and the driving force of the conveyor belts is gradually relieved as the article approaches the end of its movement along the 5 stacking plate. Means is provided for varying the angularity of the delivery run of the belts 108 relative to the stacker plate. The means here shown comprises a pair of angles 111 adjustably mounted on the plates 36 and 37. Lifting 10 the belts at this point extends their carrying 15 effect farther into the stacking device. This may be desirable in the case of heavier and stiffer articles. When the articles are lighter it may be desirable to lower the belts so as to avoid any tendency to crumple the article as it moves into the stacker against the end stop.

Means is provided for supporting a pile of 20 stacked articles above the free end of the stacker plate 105. This means comprises a pair of vertically extending plates 112 on opposite sides of the pile and mounted for vertical reciprocation. The plates 112 are guided by blocks 113 which move loosely in slots 114 which extend through the stack housing 115 and registering slots in the housing support 116. The blocks 113 have larger cover blocks 117 on their outer faces to hold the plates 112 in position.

Means is provided for reciprocating the stack holding plates 112 downwardly as the free end 30 of stacker plate 105 moves upwardly so that the individual movement of each of these portions of the stacker device is half of that which would be required of the stacker plate if it alone were required to move the folded article to position 35 above the supporting plates 112. To this end the plates 112 are carried by a yoke 118 which is pivotally connected at its lower end to an arm 119a of a T-shaped member 119 which is pinned to a shaft 120 which in turn is journaled in 40 brackets 121 connected with the frame. Another arm 119b is connected by the link 122 with the stacker plate 105. A third arm 119c is pivotally connected with a rod 123 which extends to the forward end of the machine and is there connected with actuating mechanism to be later described.

To prevent oscillation of the pile of stacked articles each time a new article is added to the bottom of the pile, I provide auxiliary stack holding arms 124 which take over the job of holding the pile of stacked articles each time the arms 112 move downwardly from their uppermost position shown in Fig. 6. It will be noted that the upper ends of the arms 112 are bent inwardly at 112a which serves several purposes. As the folded article is moved above the arm portions 112a by movement of the stacker plate the inwardly and upwardly inclined surfaces of the portions 112a guide the article smoothly past the arms 112 and into the stack. At the same time they cam the auxiliary arms 124 outwardly as will presently appear. These auxiliary arms have prongs 124a which enter through suitable openings 125 in the housing 115 so that the prongs engage against the arms 112 and are yieldingly urged inwardly by coil springs 126. Thus when the arms 112 move down the prong portions 124a slide inwardly along the arm portions 112a beneath the lowest article in the stack and remain there until the arm portions 112a again return to their uppermost position at which time the prongs 124 are again cammed outwardly and the stack is again supported by the arm portions 112a. Referring to Figs. 4 and 7, it will be noted that the upper edges of the arm

portions 112a slope downwardly and toward the rear in such a fashion that they are substantially aligned with the plane of the stacker plate when the plate 105 and the arm portions 112a pass each other in opposite directions at the time a new article is placed at the bottom of the stack.

Means is provided for counting the articles in the stack and marking the stacked articles in numbered groups by positioning an article out of line with the rest of the stack. To this end a stop 127 normally extends upwardly through a suitable opening in plate 105 and most of the articles are stopped against the member 127. At predetermined intervals this stop is moved downwardly permitting one article to move against the end stop 128 thus causing one article to extend beyond the normal line of the stack. The mechanism for accomplishing this is best seen in Figs. 4 and 7. A ratchet wheel 129 is rotatably mounted on the outside of the stacker frame on a shaft 130. A generally Z-shape lever 131 is mounted for free oscillation on the shaft 130 and is biased in upward position by means of spring 132. Pivotal mounted on the lever 131 is a ratchet pawl 133 urged by the flat spring 134 into engagement with the ratchet wheel. The arm 131a of the lever 131 extends into engagement with an arm 135 which is rigidly attached to shaft 120 which oscillates each time the stacker plate is reciprocated. The motion of lever 131 at each operation of the stacker is sufficient to move the ratchet wheel one tooth. A detent 129' holds the ratchet wheel against retrograde movement. The inner end of shaft 130 is bent upwardly at 130a at right angles to the portion of the shaft 130 upon which the ratchet wheel is mounted. Thus the end 130a moves in a circle by increments as the ratchet wheel advances one tooth at a time. In one position of the shaft 130 shown in dot-dash lines in Fig. 4 it lies beneath a finger 136 which is a rigid extension of the arm 127a which carries the stop 127. Thus when the shaft 130a is in the dot-dash position of Fig. 4 when the stacker plate returns to its lowermost position the finger 136 is moved in a clockwise direction against the bias of flat spring 137 causing clockwise movement of stop 127 below the top surface of plate 105 permitting one article to move beyond that point and against the stop 128. After the next stacking operation the shaft 130a has moved out of engagement with the finger 136 and the next article strikes the stop 127 as before. Thus each group of articles is counted and marked in a manner determined by the number of teeth in the ratchet wheel 129.

Mechanism is provided for actuating the stacker plate 105 and the arms 112 in timed relation to the movement of the folding blade 54 each time an article passes through the machine. Some time is consumed in the travel of the article from the cross folding rollers 46 and 47 to position in the stacking device and therefore some mechanism is required to delay the operation of the stacking device after the operation of the folding blade 54 to permit this time for article travel. Referring to Figs. 1, 2 and 3, the rod 123 which actuates the stacker mechanism extends forwardly in the machine where it is pivotally connected at 138 to an arm 139 which is pivotally supported on the machine frame at 140. A spring 141 biases the arm in a direction to return the stacker plate to its lowermost position. The arm 123 extends beyond the pivot point 138 and supports a roller 142 which 75

coacts with a cam 143 which is rigidly mounted on the sleeve 144 (Fig. 3) which is freely rotatable on the shaft 66. Rotatable with the shaft 66 is a toothed wheel 145 which is in all respects similar to the wheel 82 previously described in connection with the folding mechanism. Rigidly fastened to the sleeve 65 is a cam 146 which is adjusted to a predetermined position relative to the cam 64 which controls the cross folding blade 54. This cam 146 actuates an arm 147 which is rigidly fastened to a shaft 148 suitably journaled in the frame. One end of this shaft at 148a is bent at right angles and is adapted to initiate the action of a one-revolution clutch mechanism in exactly the same manner as the solenoid 67 initiates the action of the mechanism shown in Fig. 2. This duplicate mechanism is best seen in Fig. 1 and comprises an arm 149 rigidly fastened to the sleeve 144 and carrying a latch mechanism 150 exactly like the latch mechanism 84 previously described. This normally engages a stop on the arm 151 which performs the same functions as the arm 87 previously described. Since the other parts of this clutch mechanism are all exactly similar to those already described in connection with Fig. 2, it is thought further description here is unnecessary. A pulley 152 rotatable with shaft 66 is connected by belt 153 with a pulley 154 on shaft 106 and serves to drive the conveyor belts in the stacker.

The operation of the stacker mechanism is as follows: The cam 146 oscillates lever 147 a predetermined time after cam 64 has caused an operation of the folding blade 54. This oscillates the portion 148a of shaft 148 causing arm 151 to remove the stop from the latch mechanism 150. This causes the latch mechanism to latch the arm 149 to the toothed wheel 145 and cause one revolution of the sleeve 144 and cam 143 which moves the rod 123 rearwardly causing oscillation of the T-shape member 119 in a clockwise direction as viewed in Fig. 4 so as to raise the stacker plate 105 and to lower the stack supporting arms 112 causing a movement of an article into the stack. Further movement of the cam 143 permits the spring 141 to return the stacker plate to its lowermost position while moving the arms 112 to their uppermost position.

What I claim is:

1. Stacking apparatus comprising a stacking plate, means for holding a stack of articles above said plate, a conveyor movable with said plate, and said conveyor extending from a point above said plate to a point below said plate, whereby to deliver articles to said plate.

2. Stacking apparatus comprising a stacking plate, means for holding a stack of articles above said plate, a belt conveyor having a delivery run for delivering articles to said plate and lying in a plane intersecting the plane of said plate, and the higher end of said belt being the more remote from said plate.

3. Stacking apparatus comprising a stacking plate, means for holding a stack of articles above said plate, a belt conveyor having a delivery run for delivering articles to said plate and lying in a plane intersecting the plane of said plate, the higher end of said belt being the more remote from said plate, and means for varying the angular relation between the delivery run of said belt and said stacker plate whereby to deliver various types of fabric article to said plate in smooth condition.

4. Stacking apparatus comprising a vertically reciprocable stacker plate, vertically reciprocable

parallel arms extending above said plate, said arms having their upper ends bent inwardly to underlie a stack of articles, auxiliary arms positioned near the upper ends of said first named arms, means urging said auxiliary arms to a position beneath said stack of articles, means connected with said reciprocable arms for moving said auxiliary arms out from beneath said stack when said reciprocable arms move to their uppermost position, and means for lowering said first named arms and for simultaneously raising said stacker plate.

5. Apparatus for stacking articles in a vertical stack comprising a stacker plate movable up and down, vertically reciprocable parallel arms extending above said plate and positioned at opposite sides of the stack, said arms having their upper ends bent inwardly and upwardly, auxiliary arms positioned near the upper ends of said first named arms and spring pressed inwardly, said auxiliary arms engaging the outer faces of said first named arms when the latter are in their uppermost position, and means for reciprocating said first named arms and said stacker plate so that each moves up as the other moves down, said movements being sufficient for said plate to move an article thereon to a point above the upper ends of said first named arms.

6. Stacking apparatus comprising a stacker plate pivotally mounted at one end, arms extending above the free end of said plate and spaced on opposite sides thereof, said arms having their upper ends bent inwardly to underlie

a stack of articles above the free end of said plate, means for oscillating said plate upwardly and for moving said arms downwardly to cause an article upon the free end of said plate to pass above the upper ends of said arms.

7. Stacking apparatus for placing an article on the bottom of a vertical stack comprising a vertically reciprocable stacker plate, arms located above said plate on each side thereof holding said stack and receiving and holding an article elevated by said plate, and means for lowering said arms and for simultaneously raising said stacker plate, whereby to position an article above said arms and at the bottom of said stack with limited plate movement.

8. The combination of claim 7 with means underlying said stack of articles for supporting said stack in fixed position above said arms while said arms are lowered.

9. Stacking apparatus comprising a combined endless belt conveyor and stacker plate adapted to receive an article at one point and to stack the article at another point along the path of article travel, said conveyor delivering the article to said plate at said point, means for holding a stack of articles over said conveyor at said stacking point, and means for raising said plate in timed relation to the deposit of an article on said combined conveyor and plate at said receiving point, whereby to raise the article into said stack when the conveyor belt has brought it into position beneath said stack.

HUGH W. GABBERT.
